UNITED STATES PATENT OFFICE.

WILLIAM M. DAVIDSON, OF CHICAGO, ILLINOIS.

WATCH-INSPECTION CARD.

1,286,549.

Specification of Letters Patent.

Patented Dec. 3, 1918.

Application filed August 13, 1917. Serial No. 185,855.

To all whom it may concern:

Be it known that I, WILLIAM M. DAVIDSON, a citizen of the United States, residing at Chicago, in the county of Cook and State 5 of Illinois, have invented new and useful Improvements in Watch-Inspection Cards, of which the following is a full, clear, and exact description.

My invention relates to a new and useful 10 improvement in cards relating to watch inspection, and particularly to a system of watch inspection adapted for use by railroad corporations.

It is essential that the watches of all of 15 the members of the operating force of a railroad be inspected and corrected periodically in order that a unity of time may control their actions and the movements of trains operated by them, and thus insure the 20 safety of both passenger and freight traffic, and avoid congestion and collisions and expedite the business of the railroad.

The object of my invention is to provide 25 a series of separable interrelating cards, each possessing a suitable printed form thereon and adapted, when properly disposed of by the railroad official, the railroad employee and the watch inspector, and filled in by them after they have followed the instructions 30 contained in the same, to enable the executive department of the railroad to maintain strict surveillance over and keep track of the watches of its employees. This I accomplish by the means hereinafter fully described, and as particularly pointed out in 35 the claims.

In the drawings:

Figure 1 is a front view of the upper portion of my improved form of watch inspection 40 cards.

Fig. 2 is a similar view of the lower portion of said cards and constitutes a continuation of that shown in Fig. 1.

Fig. 3 is a view of the rear side of the 45 second card illustrated in Fig. 1, detached therefrom.

Fig. 4 is a rear view of the fourth card illustrated in Fig. 2, detached therefrom.

Referring to the drawings, 5, 6, 7 and 8, 50 represent, respectively, the cards belonging to the series that constitute my invention. These cards are, preferably, of the same

dimensions and are printed on one long strip of material, but are separable one from the other on the perforated lines 9, 9, which constitute the line of demarcation or separation of the forms printed thereon. Each of these cards bear the same number, which is, preferably, printed in red ink in the upper right hand corner of the same to indicate that they 60 all belong to the same series and pertain to the same inspection, and all of said cards have the name of the corporation, in connection with the watch inspection for which said cards are issued, at the top of the same. 65

The top card, 5, immediately below the name of the corporation, is entitled "Order for Watch Inspection", and below this title it contains the following form in which the underscored words constitute the written 70 filled in matter, which does not appear in the original blank form, to-wit:

THE LONE STAR & PACIFIC RAILWAY CO.

Order for Watch Inspection.

5236 75

Date issued, July 15, 1917

Name, John Doe

Occupation, Conductor

Address, Blue Island

Returned, July 20, 1917

Remarks: Watch in good condition.
RICHARD ROE, Watch Inspector.

40 Card 8, below the name of the corporation, is entitled "Employee's Watch Comparison Card," and contains the following form, in which the underscored words were not contained in the original blank form, but constitute the filled in matter, to-wit:

45 THE LONE STAR & PACIFIC RAILWAY CO.
Employee's Watch Comparison Card. 5236
Date, July 19, 1917.
Mr. John Doe.
Occupation, Conductor, Div. Chicago.

50 Maker of Mov't. Elgin Watch Co. Grade name or
Movement No. 32128. Grade number 1st.
Last Cleaned or Rep. Date, July 19, 1917.
RICHARD RON, Watch Inspector.

55 _____ City of Chicago.
PRESERVE THIS CARD.—It will be taken up next
quarterly inspection.
NOTE: If watch is rejected, Inspector must return this
Comparison Card at once to the Division Supt., giving all
the facts.

Employed receiving this card must at the end of the quarter surrender it to an Inspector who will promptly forward it to National Railway Time Service Co. Chicago. This card renewed only by Division Superintendent.

This card 8 is preserved by the employee and on the reverse side of it the following form is printed for keeping a correct record of

the dates when the employee's watch was 65 inspected, to-wit:

TIME RECORD.

INSTRUCTIONS—Each employee whose watch is subject to inspection must report to an Inspector every two weeks, and oftener when convenient, in order that the condition of his watch may be noted and a record of its performance made on the "Employee's Card" by the Watch Inspector. Employees must have their certificates at hand at all times and present it for examination when called for by an officer.

NATIONAL RAILWAY TIME SERVICE Co.

Card 5, after it is filled in, is torn off and retained by the proper railroad official. 95
Card 6, after it is filled in, is sent, together with cards 7 and 8 to the watch inspector. After the inspection of the watch has been made, the inspector fills in the form on the back of card 8; makes the necessary memorandum on the front and back of card 8, and 100

zandum on the front and back of card 8 and tears it off and sends it to the general watch inspection company that supervises the inspection for the railroad. If the watch is in good condition, the local inspector fills in 105 the certificate on card 7, signs it and mails it or otherwise delivers it to the railroad official. If the watch is not in good condition the inspector does not detach card 8, but leaves it with the railroad official, and the 110 latter can give the employee such orders relative to his watch as the circumstances may seem to warrant. Card 8 after being filled out by the local inspector is given to the employee to carry during the quarterly 115 inspecting period, and notations of the rating of his watch are entered weekly by the local inspector, together with a time record when said notations were made, and this 120 is carried by the employee.

card 8 is collected at the end of the quarterly period at which time a new series of watch inspection cards are issued. The surrendered employee's watch comparison card for the expired quarter is, in the meantime, surrendered to the said general watch inspection company and from cards 6 and cards 8 it makes up reports of the condition of the watches of said employees and sub- 120
125

mits the same to the officials of the railroad company.

What I claim as new is:

1. Cards for watch inspection comprising a series of four separably connected cards, each having the same identifying data, one of which contains an order of inspection adapted to be detached and retained by the corporation issuing the same, another of which contains an order of inspection and is addressed to a watch inspector and a certificate of inspection, and employee's watch comparison card; said inspector's order for watch inspection adapted to be detached from the certificate of inspection, which latter is adapted to be detached and returned to the said corporation.
2. Cards for watch inspection comprising a series of four separably connected cards all having the same identifying data and number impressed thereon, one of which contains an order of inspection adapted to be detached and retained by the corporation issuing the same, another of which contains an order of inspection and is addressed to a watch inspector, and a certificate of inspection, and employee's watch comparison card; said inspector's order for watch inspection adapted to be detached from the certificate of inspection which latter is adapted to be detached and returned to the said corporation.
3. Cards for watch inspection comprising a series of four separably connected cards all correspondingly designated by the name of the issuer and the same number, one of which contains an order of inspection adapted to be detached and retained by the corporation issuing the same, another of which contains an order of inspection and is addressed to a watch inspector, and a certificate of inspection, and employee's watch comparison card; said inspector's order for watch inspection adapted to be detached from the certificate of inspection, which latter is adapted to be detached and returned to said corporation.
4. The combination with an order for watch inspection, of a watch certificate and an employee's watch comparison card, each of which forms bears the same identifying data, substantially as set forth.
5. The combination with an order for watch inspection, of a watch certificate, an employee's watch comparison card, and a time record adapted to be used in conjunction therewith, each of which forms bears the same identifying data, substantially as set forth.
6. The combination with an order for watch inspection, of a watch certificate, an

employee's watch comparison card, each of which members bears the same identifying data, and a time record on the back thereof.

7. The combination with an order for watch inspection, and an inspector's report used in connection therewith, of a watch certificate, and an employee's watch comparison card; each of which members bears the same identifying data.

8. The combination with an order for watch inspection, and an inspector's report used in connection therewith, of a watch certificate, an employee's watch comparison card, and a time record adapted to be used in conjunction therewith, each of which forms bears the same identifying data, substantially as set forth.

9. The combination with an order for watch inspection adapted to be retained by the party issuing the same, and a watch inspection order adapted to be issued to a watch inspector, of a watch certificate and an employee's comparison card, each of which forms bears the same identifying data, substantially as set forth.

10. The combination with an order for watch inspection adapted to be retained by the party issuing the same, a watch inspection order adapted to be issued to a watch inspector, and a time record adapted to be used in conjunction therewith, of a watch certificate, and an employee's comparison card, each of which forms bears the same identifying data, substantially as set forth.

11. The combination with an order for watch inspection adapted to be retained by the party issuing the same, and a watch inspection order adapted to be issued to a watch inspector, of a watch certificate, an employee's comparison card, and a time record adapted to be used in conjunction with the latter, each of which forms bears the same identifying data, substantially as set forth.

12. The combination with an order for watch inspection adapted to be retained by the party issuing the same, and a watch inspection order adapted to be issued to a watch inspector, a watch inspector's report used in connection therewith, a watch certificate, an employee's watch comparison card, and a time record adapted to be used in conjunction therewith, each of which forms bears the same identifying data.

In witness whereof I have hereunto set my hand this 2nd day of August, 1917.

WILLIAM M. DAVIDSON.
